PNEUMATIC TOOL FOR CLIPPING WIRES

Howard R. Fischer, New Hartford, Livio F. Marcantonio, Utica, and Marcel P. D'Haem, New Hartford, N.Y., assignors to Chicago Pneumatic Tool Company, New York, N.Y., a corporation of New Jersey

Filed May 12, 1961, Ser. No. 65,143

Term of patent 14 years

(Cl. D54—13)

FIG. 1

FIG. 2

FIG. 3

FIG. 4

FIG. 5

FIG. 6

FIG. 1 is a side elevational view of a pneumatic tool for clipping wires, showing our new design;

FIG. 2 is an elevational view taken from the side opposite FIG. 1 thereof;

FIG. 3 is a plan view thereof;

FIG. 4 is a bottom view thereof;

FIG. 5 is a front end view thereof; and

FIG. 6 is a rear end view thereof.

We claim:

The ornamental design for a pneumatic tool for clipping wires, as shown.
